(57) **CLAIM**

The ornamental design for a neurovascular stent, as shown and described.

DESCRIPTION

FIG. 1 is a top view of a neurovascular stent, according to an embodiment of the design, the bottom view being identical to the top view.

FIG. 2 is a left side view of the neurovascular stent, according to the embodiment of the design, the right side view being identical to the left side view.

FIG. 3 is a front view of the neurovascular stent, according to the embodiment of the design, the rear view being identical to the front view; and,

FIG. 4 is a top, right, front perspective view of the neurovascular stent, according to the embodiment of the design.
